CARD FILE COMPRESSOR

Raymond L. Myers, Vestal, N.Y., assignor to Ray Myers Corporation, Endicott, N.Y., a corporation of New York

Refiled for abandoned application Serial No. 504,338, April 27, 1955. This application October 19, 1956, 10 Serial No. 617,177

2 Claims. (Cl. 129—28)

This invention relates to a card file compressor, and more particularly to the structure of a compressor which may be suitably mounted on a single slideway in a tray or drawer used for filing cards.

File cards are commonly used for tabulating various data thereon by means of punch marks, and these cards are fed through an accounting or tabulating machine for recording the various data indicated by the punch marks. In order that the cards may be fed readily and properly through the machine, it is necessary that the cards be held in a non-warped and well protected condition. It is, therefore, desirable that the cards stored in a file tray or drawer be held under high compression and protected against injury. Various types of compressors have been employed heretofore, but those which are slid into position and clamped against the cards manually may not provide a sufficient pressure to hold the cards in the required shape. Also, it is important that the compressor employed for the purpose occupy the minimum of space in the tray and that it may be readily slid into position and easily operated and particularly that the force applied by the compressor may be multiplied through a mechanical movement sufficiently to give a high pressure against the cards.

The primary object of this invention is to satisfy these requirements and to provide a compressor in a card file tray which may be operated mechanically to give a high compression on the cards and yet may be readily released therefrom.

Another object of this invention is to provide a card compressor which may be mounted on a single wall of a file tray or drawer, and wherein its construction is such that cards may be held under adequate compression, as is particularly required for punched cards which are to be protected against warpage and injury.

A further object of this invention is to provide a compressor with a mechanical movement which insures that after the compressor has been brought up against the cards it may be moved to a further extent without large manual effort to force the cards together and hold them in a non-warped condition.

Another object is to provide a compressor construction which may be mounted on a side wall of a tray and will give a positive card compression and hold the cards so tightly packed that the tray may be carried in any position without the cards spilling out. Other objects will be apparent in the following disclosure.

Referring to the drawings illustrating one embodiment of the invention:

Fig. 1 is a perspective view of a compressor mounted on a slideway with the card file tray wall omitted in which the compressor is in an inoperative, non-compressing position;

Fig. 2 is a similar perspective view showing the tray bottom and a vertical tray wall in which the compressor is mounted and with the compressor in a card compressing position;

2

Fig. 3 is a sectional detail of the compressor slide parts and tray wall shown in Fig. 2;

Fig. 4 is a diagrammatic vertical sectional detail on the line 4—4 of Fig. 2 showing the relation of the compressor lever to the associated parts;

Fig. 5 is a diagrammatic top plan view showing in exaggeration the angular arrangement of the compressor relative to the opposed tray wall;

Figs. 6, 7 and 8 are diagrammatic sketches showing the relative positions of the operating handle and the pawl which applies compression to the cards; and

Fig. 9 is a fragmentary perspective view of a tray body in which the rack bar and compressor are to be mounted.

The preferred tray construction comprises sheet metal fashioned to form a side wall 10 integral with and perpendicular to a bottom 11. These in turn are suitably connected with an end wall 12 and an opposing end wall 13, which may be constructed as herein described and as claimed in my copending applications Serial No. 617,174, now Patent No. 2,895,485, issued July 21, 1959, and No. 617,176 and filed on even date herewith. The side wall 10 is provided with a slideway or compressor track formed of a U-shaped member 14 having two flanges 15 in the same plane and parallel with but spaced from the inner face of the side wall 10. The side wall 10 may also have a U-shaped flange providing a surface 16 which lies in substantially the plane of the sides of the flanges 15 which engage the cards, so that cards may rest adequately against and be aligned by those surfaces 15 and 16.

The compressor comprises a standard 20 of sheet metal which is integrally connected to a U-shaped slide plate 21 having inwardly curved end portions providing flanges 22 which fit and slide relative to the under sides of the track plates 15. The standard 20 is somewhat U-shaped for strength and provided with an in-turned end flange 24 which rests on and is welded to the slide plate 21. The out-turned edges 23 of the open side (Fig. 4) of the U-shaped standard 20 are rigidly welded to the face of a further plate 25 having a strengthening peripheral flange 26. The plate 25 provides a plane surface arranged at a required angle to engage the face of the adjacent file card. This plate 25 is preferably arranged at an angle slightly less than 90°, such as 87°, relative to the side wall 10 (as shown in Fig. 5). Thus the end of the plate furthermost from side wall 10 provides a greater pressure against the cards positioned intermediate plate 25 and end wall 12 than does the end of the plate 25 adjacent side wall 10. It should be mentioned that the inner surface of the end wall 12 of the tray (Fig.

9) which opposes this slightly inclined plate is arranged at 90° to the card engaging surfaces of flanges 15 and 16 of the tray, so that the slight inclination of the plate 25 is sufficient to give a clamping pressure against the outer portions of the stack of cards, as shown in exaggerated form in Fig. 5.

In order to clamp the plate 25 against the cards with the desired compressive action, I have provided a rack bar on a wall of the tray and pawl carried by the compressor which is manually operated by a lever. This comprises a rack bar 30 (Fig. 2) welded on the lower face 31 of the U-shaped piece 15 of the tray. As indicated in Figs. 6, 7 and 8, the teeth 32 of the rack bar have vertical faces 33 facing toward the front of the tray or in the direction of movement of the compressor 65 to compress the cards.

The teeth may be formed as shown by cutting U-shaped slots in a metal bar in a spaced arrangement, which provides parallel teeth with their sides substantially parallel. The standard is held in an adjusted position relative to the rack bar by means of a rocking pawl 35 which is mounted for movement both pivotally and

transversely of the standard. The pawl is preferably formed as a lateral projection fixed on the end of a rod 36 which extends horizontally or lengthwise of the standard relative to the rack bar. This rod 36 is shown as mounted at its outer right hand end (Fig. 2) in the pivot hole 37 in the inwardly bent flange 38 which is formed on the outer end of and integral with the standard 20. A further flange 39 (Figs. 2 and 4) is formed by cutting a U-shaped slot in the central plate portion of the standard and bending the free metal inwardly to extend at right angles to the inner face of the standard 20 and form an intermediate or central pivotal support for the rod 36.

The end of the rod which carries the pawl 35 is mounted in an elongated vertical slot 40 which extends through the flange 24 and the slide plate 21. This slot 40 provides for a transverse movement of the pawl relative to the standard, so that the free end of the pawl may pivot about a tooth groove. The lower end of the slot 40, which is elongated transversely of the standard, is aligned with the two bearing holes in the flanges 38 and 39. The rod 36 has sufficient resiliency so that it may be bent in that slot transversely of the standard. The pawl on the end of the rod is urged toward the rack bar by a coiled tension spring 42 suitably secured to the rod and to the lower horizontal wall (Fig. 2) of the standard 20, so that the pawl end of the rod may be lifted when the pawl is swung about its free end through a vertical or dead center position and then return to the bottom of the elongated slot, while the pawl is always engaging the tooth groove.

The rack bar teeth are so shaped that the grooves therebetween form fulcrums or pivot points about which the free end of the pawl 35 may pivot, and the tooth face toward the cards is so shaped as to provide a pawl confining space having a surface against which the pawl may brace to compress the cards. The sides of the slot 40 in the standard 20 (Fig. 2) provide bearing surfaces parallel with the plate 25 for confining the rod 36 laterally, and the right hand surface of the slot receives the lateral thrust of the pawl when the latter is braced against a tooth to compress the cards. The spring urges the pawl rod 36 towards the end of the slot 40 nearest the rack bar and holds the pawl 35 in engagement with a tooth slot when the handle 45 has positioned it for a compressing movement of the compressor.

A pivoted handle lever 45 (Fig. 4) is provided with a curved edge 46 which serves as a hand grip. The handle is fixed at its lower end permanently to the rod 36, as by having a portion wrapped around the rod (Fig. 2) and welded in place at 47. This rod 36 thus forms a pivot for the handle lever 45. The U-shaped standard plate 20 terminates at 51 beyond or at the left of this lever 45 (Fig. 1), so that the lever may be fastened to the rod 36 and be rotated manually. The handle 45 has a flange 48 projecting at right angles from its exposed vertical front face which has a vertical edge 49 adapted to be brought into engagement with the rear of the wall 25 when in an end clamping position. This limits the handle motion.

The tray structure may be widely varied. As shown in Fig. 9, it comprises a suitable front wall 12 of sheet metal secured to the side wall 10 and a low side wall 61. The bottom 11 may be integral with the side walls 10 and 61, such as by being shaped from a single piece of sheet metal, and these parts are suitably welded or secured to the front wall. The rear wall comprises an open metal frame 13 suitably welded or secured to the side walls and bottom, and this frame provides hand grips for suspending and carrying the tray vertically.

In its operation, the lever handle 45 may be thrown away from the cards and the pawl is moved into a forwardly inclined or non-bracing position as shown in Fig. 6, wherein the edge 49 (Fig. 1) of the flange 48 is remote from the card compressing plate 25. The

pawl is then inoperative. When the handle 45 is swung outwardly relative to the plate 25, the pawl 35 is in a forward position (Fig. 1) and disengaged from the rack bar teeth which permits the compressor slide 21 to move freely on the surfaces 15 and 16 towards and from the cards. After the compressor plate has been moved up against the file cards, the lever 45 may be swung upwards and forward towards the plate 25 through a short distance to swing the pawl 35 into engagement with one of the adjacent teeth grooves of the rack bar, as shown by the relative positions of the compressing plate 25 and the pawl 35 in Fig. 6. When the lever 45 is swung further toward the plate 25, the pawl 35 passes through a vertical or dead center position, as shown in Fig. 7, and the rod 36 is bent upwardly in the slot 40 against the tension of the coiled spring 42. This permits the pivot center of the pawl to move transversely of the compressor standard. When the hand lever 45 is moved to a point where the edge 49 engages the face 25, as shown in Figs. 2 and 8, the pawl which has remained in the same tooth groove is urged by the manual swinging of the lever and the force of the spring 42 to thrust the compressor plate 25 tightly against the cards. The strength of the spring is such as to hold the pawl in place, and the pawl is so inclined as to form a brace against any rearward motion of the compressor plate under the forces applied by the compressing action.

For releasing the cards, it is merely necessary to pull the handle lip 46 away from the compressor plate 25 and this causes a reversal of motion of the pawl, in which its pivot rod 36 again moves transversely in the slot and the pawl moves from the position of Fig. 8 through that of Fig. 7 to the inclined position of Fig. 6, and further movement of the handle away from plate 25 causes the pawl to be moved fully from the Fig. 6 position to that of being released from the rack bar which permits sliding the compressor freely. This release of the pawl does not require compression of the cards during the action, since the releasing movement of the compressor plate is away from the cards. The diagrammatic sketches of Figs. 6, 7 and 8 show the relative movement of the compressor plate as the pawl 35 swings through the various positions.

While the file tray has been illustrated in Fig. 9 as having high and low side walls, it will be understood that the file tray could have two high side walls. In that case the compressor is mounted on only one wall and there is but a single slideway and a single slide supporting the compressor. It is, however, required that the tray have a side wall, a bottom wall and an end wall against which the cards may be compressed and it is preferred that the compressor be mounted solely on one of the walls for movement toward the cards. The compressor is slidably mounted on a track on that wall and it carries a pivoted pawl, such as a gear tooth or pawl, which engages a rack bar suitably mounted or formed on the side wall of the tray. The pawl is so pivotally mounted on the standard that it may be swung by a cam or lever action from a fully released position into engagement with the rack bar and thereafter pivot about its point of contact with the rack bar for forcing the compressor forward against the cards. The pawl is manually moved about its rack bar pivot across dead center into a position where it braces the compressor against the cards. Means, such as the spring 42, serves to urge the pawl into engagement with the tooth groove of the rack bar and to hold the pawl in its final braced position after it has passed dead center. That is, the pawl is mounted both for pivotal movement and for a transverse movement across dead center relative to the rack bar, so that when the pawl is swung from the position of Fig. 6 to that of Fig. 8 while in engagement with the same rack bar groove it causes the compressor to move forward toward the cards by that distance in

volved in swinging the pawl relative to the stationary pivot of the groove of the rack bar.

It will now be appreciated that various modifications may be made in this construction within the principles of this invention to provide this pivotal movement of the pawl about the point at which it engages the rack bar and thereby provide the desired thrust against the cards. Hence, various mechanical movements may be employed for swinging the pawl about that rack bar point and for holding or urging it in a final clamping position. Hence, various modifications may be made in the construction within the scope of this invention. The above disclosure is therefore to be interpreted as setting forth the principles and a preferred embodiment of the invention and not as imposing limitations on the appended claims.

This case is a refile for my application Serial #504,338, filed April 27, 1955.

I claim:

1. In combination with a rectangular card file tray having bottom and side walls and at least one end wall, a horizontal slideway track secured to one of said side walls and extending longitudinally of said tray, a rack bar secured to said one side wall parallel to said track, a compressor standard transversely mounted in said tray intermediate the side walls thereof and slidably connected at one end to said slideway track solely for longitudinal movement in said tray to compress the file cards between the compressor standard and one end wall of the tray; the improvement which consists of means for initially locking the compressor standard in a desired longitudinal position in the tray and for subsequently displacing the standard a small distance toward the associated end wall to compress the file cards therebetween, comprising a horizontal resilient pawl rod within said compressor standard substantially normal to the rack bar, said compressor standard having an end wall adjacent the tray side wall to which the rack is attached, said compressor standard end wall having a vertical slot therein through which one end of said pawl rod extends and is guided thereby

during vertical movement of said rod end, said rod end terminating in a pawl element which removably engages the teeth of the rack bar, said pawl rod being rotatably connected at its other end to said compressor standard in fixed bearing means, spring means connected to said compressor standard normally biasing the free end of said pawl rod toward one extremity of said vertical slot and said pawl element toward said bar, and means for rotating said pawl rod, said pawl rod being rotatable to a first position wherein said pawl element angularly extends into the groove between a pair of rack teeth into contact with the rear surface of the rack tooth which is closer to the tray end wall, said pawl rod being portable from said first position to an intermediate position wherein said pawl element is intermediate the rack teeth and normal to the axis of the rack with the pawl rod bent in a cantilever manner about its fixed rotatable connection to the compressor standard toward the other extremity of the slot in the standard end wall, and said pawl rod being rotatable from said intermediate position to said locked position wherein the pawl element angularly extends in engagement with the forward surface of the other rack tooth, said compressor standard being moved toward said tray end wall during the rotational movement of said pawl rod from said first position to said locked position.

2. Apparatus as defined in claim 1 wherein said means for rotating said pawl rod comprises an operating lever rigidly connected at one end to said pawl rod adjacent the bearing connection of the rod to the compressor standard.
